UNITED STATES PATENT OFFICE.

CHARLES L. LOW, OF FRESNO, CALIFORNIA, ASSIGNOR TO LISENBY MANUFACTURING COMPANY, OF FRESNO, CALIFORNIA, A CORPORATION.

PAPER FEED, PRINTING, AND INKING CONTROL MECHANISM FOR PRINTING PRESSES.

Application filed June 27, 1924. Serial No. 722,732.

This invention relates to improvements in printing presses, and particularly to a comparatively small press, adapted to print letters, circulars and the like and having a reciprocable moving bed consisting of a central type-form and ink plates at each end thereof; a rotatable printing cylinder adapted to be lowered into cooperating relation with the type form at a predetermined time; 10 ink supply means for the plates, a paper feeding structure, a counter mechanism; a coordinated driving mechanism for all the moving parts, so that all the operations normally take place automatically in proper sequence.

The principal object of my invention is to provide a mechanism, to be applied to such a press, whereby if the operator fails to feed a sheet to the paper feed structure; or feeds 20 more than one sheet at a time thereto or a sheet is thicker than the others being run through the press at the time, the printing cylinder will not be lowered into engagement with the type on the form; the counter will 25 not be actuated; no further ink will be distributed by the duct rolls onto the ink plates; and when more than one sheet is on the feeding structure or such sheet is excessively thick, such sheets will be prevented 30 from passing to the printing cylinder.

By reason of this mechanism, which functions automatically under the above conditions and as long as the press is operating the type is prevented from becoming over- 35 inked, the cylinder will not be impressed by the type (a cause of double-sided impressions frequently seen); no sheets can pass through the press but what actually receive the impression of the type, and the counting mechanism will denote the correct number of sheets actually printed.

Another object is to provide for the adjustment of the control member of this mechanism, so that it may be easily set to 40 function with any thickness of paper which it may be desired to run through the press.

I have also provided means for throwing the entire mechanism out of operation, should this be desired, without interfering 45 with the normal functioning of the press.

A further object of the invention is to produce a simple and inexpensive device and yet one which will be exceedingly effective for the purposes for which it is designed.

These objects I accomplish by means of

such structure and relative arrangement of parts as will fully appear by a perusal of the following specification and claims.

In the drawings similar characters of reference indicate corresponding parts in the several views:

Fig. 1 is a side elevation of the complete press, with the moving bed at the forward end of its stroke.

Fig. 2 is an enlarged fragmentary side view of the press, with the frame in skeleton, and with all parts omitted which are not pertinent to this invention. In this view, the moving parts are in the same position as in Fig. 1.

Fig. 3 is a fragmentary section enlarged, of the feed conveyor, showing a paper distinguishing mechanism, in a position corresponding to Fig. 2. This mechanism controls the movements of the printing cylinder and inking duct-rolls.

Fig. 4 is a fragmentary view showing a drop roll of the feed conveyor, and the mounting thereof, in its position relative to the lower tape roll of the conveyor corresponding to the position of the parts in Figs. 2 and 3.

Fig. 5 is a view similar to Fig. 2, with the parts moved so that the printing cylinder is in printing relation with the type form, and just at the beginning of the printing period.

Fig. 6 is an enlarged fragmentary view of the lower end of the feed conveyor and printing cylinder, with adjacent parts, showing the position of the conveyor feed-guides and drop rolls just prior to the lowering of the printing cylinder to full printing position.

Fig. 7 is a view similar to Figs. 2 and 5, showing the position of the parts just as the paper distinguisher has failed to be actuated, due to the lack of, or too many, sheets on the conveyor.

Fig. 8 is a fragmentary view of the start- 100 er-roll arrangement of the conveyor.

Fig. 9 is an enlarged fragmentary view of the paper distinguishing mechanism, and the trip-latch structure, showing the latch disengaged by reason of the engagement of a sheet of the proper thickness on the conveyor with said mechanism.

Fig. 10 is a similar view, showing the latch engaged by reason of the failure of the distinguishing mechanism to be actu- 110

ated, due to the absence of a sheet from the conveyor.

Fig. 11 is a fragmentary section of the printing cylinder and its mounting, and the connection of the trip-latch structure therewith.

Figs. 12 and 13 are diagrams of the cylinder and type form, showing the relationship of the two, and certain cooperating members, when the form is at the forward limit of its movement, and at the start of the printing position, respectively.

Referring now more particularly to the characters of reference on the drawings, the numeral 1 denotes the frame of the press of suitable design, slidably mounted in which for longitudinal reciprocatory movement is the moving bed 2, carrying the type form 3 and the ink plates 4 at both ends of the same,

20 The bed is continuously reciprocated through a given distance by means of a link 5 connected thereto and to a rocking lever 6 pivoted on the frame, movement being imparted to this lever by means of a connecting rod 7 attached thereto and to the crank 8 of a shaft 9. This shaft carries a gear 10 driven from a pinion 11 on a shaft 12, the latter being driven from an electric motor 13 or the like.

30 Extending lengthwise of and fixed along one edge of the bed 2 is a rack 14 meshing with a gear 15 turnably mounted on a transverse shaft 16 journaled adjacent its ends in bearing blocks 17 on the frame 1. The shaft 16 has an eccentric portion 18 intermediate its ends on which is turnably mounted the printing cylinder 19, extending across the form 3. This cylinder has a radial lug 20 slidably projecting into a radial slot 21 in the gear of greater length than the lug (see Fig. 11). In this manner the gear is connected in driving relation with the cylinder, and with the reciprocation of the bed, the cylinder and gear oscillate in unison, regardless of any rotation of the shaft 16 and of the offset relation of the eccentric part 18 therewith.

50 The shaft 16 is oscillated and consequently the cylinder moved up and down, through a certain arc and at a predetermined time, relative to the movement of the bed 2, by means of an arm 22 fixed on one end of the shaft, the free end of said arm being attached to a rod 23 connected at its other end to the upper end of a lever 24. This lever is pivoted intermediate its ends on the frame 1, and carries on its lower end a roller 25 adapted to ride on a cam 26 fixed on the shaft 9 in predetermined relation to the 60 crank 8.

A spring 24^a acts on the lever to normally hold the roller against the cam. This cam is designed so that the cylinder will be lowered and will remain in that position during a peripheral movement of the cylinder about

equal to the length of the form 3; and will be raised clear of the form for the remainder of the revolution of the cam and shaft 9. The driving parts are so correlated with each other that this lowered position of the cylinder is had while the type form is moving under the same in a rearward direction.

70 For inking the plates 4 and the type on the form 3, I provide ink fountains 27 above the plane of the plates and toward the opposite ends of the frame 1. These fountains are preferably of the type shown in my co-pending application on the same, filed July 1st, 1924, Serial No. 723,513. Each fountain includes a roller 28, intermittently rotated in 80 a constant direction by means of a common form of pawl and ratchet structure 29, the pawl being mounted on an arm 30 depending from and concentric with the roller. The arms 30 of both fountains are connected by 85 rods 31 to a vertical lever 32 pivoted at one end on the frame and operatively connected at its opposite end to the rocking lever 6. Ink from the fountain rollers is placed on the plates 4 by means of duct rollers 33 engageable alternately with the rollers 28 and with the plates, and mounted on arms 34 fixed on shafts 35 pivoted transversely in the frame 1 under the plane of the plates. Springs 36 (see Fig. 1) act to hold the duct 90 rolls normally engaged with the fountain rolls. The duct rolls are caused to be moved from engagement with the fountain rolls to engagement with the plates by means of rollers 37 mounted on horizontal arms 38 100 fixed on the shafts 35, and which rollers are engaged and lowered by sloping cam surfaces 39 under and at the ends of the plates 4. The ink thus fed onto the plates at one end thereof is distributed over the entire area of 105 the plates by means of suitable angle-distributor roll units 40, and the ink is spread onto the type on the form 3 from the plates by the form roller units 41 (see Fig. 1). These latter units are of special construction and 110 mounting, and form the subject matter of my co-pending application on the same filed July 1st, 1924, Serial No. 723,515.

Depending from and fixed on the shafts 115 35 are arms 42 to the lower ends of which are connected horizontal bars 43 and 44 extending toward each other, the latter overlapping the former and resting thereon at their adjacent ends. The free end of the bar 43, has a cam portion 43^a thereunder, projecting below the normal level of the bar, and normally riding on the upper end of a vertical trip or control bar 45 pivoted intermediate its ends on the frame 1. This bar is connected to the lever 24 by a link 46 which 120 is pivotally connected to the lower end of the bar 45 and at its opposite end has longitudinally spaced notches 47 on its under face, either of which engages a pin 48 on the lever above its pivot. In this manner, the 125

operative length of the link may be altered at will, for a purpose as will appear.

The bars 43 and 44 each has a notch 49 in its upper face, to cooperate with corresponding pawls 50 mounted on the frame, and prevented from downward movement below a predetermined point by projecting pins 51 thereunder.

A counting device, of any standard form, indicated generally at 52, is actuated from the lever 24 by a rod 53 extending therefrom to the horizontal rocking arm 54 of the counter (see Fig. 1).

To feed sheets to the printing cylinder one by one and in timed order with the operation of the moving bed and cylinder, I employ a feed conveyor including side rails 55, upper and lower tape rolls 56 and 57 therein suitably driven from the shaft 12, and tapes 58. Starter rolls 59 are engageable with the upper tape rolls 56, being supported from arms 60 turnably mounted on a shaft 61 journaled in and between the side rails 55. The raising and lowering of these rolls in certain timed relation with the movements of other parts, and certain other features included with the feeding structure, form of themselves no part of the present invention, these features being particularly described and claimed in my copending application on a "semi-automatic feed device" filed June 27th, 1924, Serial No. 722,732.

The drop rolls 62, engageable with the lower tape rolls 57, are mounted on a shaft 63 which is supported at its ends on arms 64 which are journaled intermediate their ends on the side rails. The forward ends of these arms have vertical adjustment screws 65, the lower ends of which are engaged by lugs 66 fixed on a transverse shaft 67 journaled in the side rails ahead of the arms 64. Spring means 68 (see Fig. 6) act on the arms 64 to hold the drop rolls raised.

Adjustably fixed on the shaft 67 and extending rearwardly of the drop rolls are the feed guides 69, whose lower ends normally engage and project below the feed guide tongues 70 which rest on the rolls 57 between the tapes, and extend beyond and in substantial alinement with the rear end of the tapes to a point adjacent and in line with the feed rolls 71 which lie just ahead of the cylinder.

By reason of this drop roll and feed guide arrangement, it will be seen that if the shaft 67 is rotated to cause the lugs 66 to engage and raise the adjacent ends of the arms 64, the drop rolls will be lowered, while at the same time the feed guides will be raised.

Such movement is normally imparted to the shaft 67 at predetermined times by means of an arm 72 connected to the outer end thereof, the free end of said arm carry-

ing a roller 73 which rides on a cam 74 mounted in connection with the arm 22. This cam has three surfaces, all different distances from the axis of the shaft and all concentric therewith. The first or normally forward surface A is such that when the roller 73 is riding thereon, the feed guides are in their lowermost position and the drop-rolls are raised, as shown in Figs. 2, 3, and 4.

The second surface B is relatively short and is so disposed that when the roller 73 is riding thereon, the guides 69 will be fully raised and the drop rolls lowered as shown in Fig. 6. The third surface C is lower than the surface B, but higher than surface A, being so designed that when the roller is riding thereon, the drop rolls will be raised from the tape rolls, but the feed guides will still be clear of the tongues 70, as shown in dotted lines in Fig. 6. The purpose of this arrangement will be seen hereinafter.

Turnably mounted on the shaft 67 between the guides 69 is a sleeve 75 fixed at one end on, and sloping downwardly and rearwardly from which, is a flat shoe 76 of resilient material, normally projecting between and below the tapes 58 to a point adjacent the rear tape roll 57, and resting at its lower end on a transverse rod 77 mounted on the side rails 55. Also fixed on and projecting rearwardly from the sleeve 75 above the shoe is a horizontal rigid ledge 78, whose rear end extends parallel to the shaft and is quite thin. An adjustable screw 79 is mounted in this ledge and bears down on the shoe 76. A transverse shaft 80 is journaled in the side rails above and to the rear of the shaft 67, and has fixed thereon a depending block 81 to which is fixed a forwardly projecting horizontal rigid ledge 82. This ledge is similar in size, and of the same thickness, as the ledge 78, and its forward edge is normally but very slightly to the rear of the rear edge of the ledge 78, but somewhat above the level of the latter.

It will be noted that if the screw 79 is turned one way or the other, the angle of divergence between the rigid ledge 78 and the resilient shoe will be altered, causing the rear edge of the ledge to be closer to or farther from, the portion of the shoe directly thereunder. In operating the press therefore, this screw is adjusted according to the thickness of the sheets being run through at the time, and in such a manner that when the shoe is raised by a sheet of the proper thickness, so that the shoe is above the tapes and tongues a distance equal to the thickness of said sheet, the ledges 78 and 82 will be in exact horizontal alinement. The purpose of this arrangement will be seen later.

Fixed on the shaft 80 is an arm 83, whose outer end carries a roller 84 bearing on a disc 85 fixed in connection with the cylinder drive gear 15. This disc has a flattened portion 86 for a certain extent of its periphery. A spring 87 normally acts on the arm 83 to hold the roller against the disc. Fixed on the shaft 16 at the end thereof adjacent the gear 15 is a smaller disc 88 having a peripheral ratchet-notch 89. Adapted to seat at one end in said notch, and disposed tangentially of the disc 88, is a rigid trip-latch 90, pivoted intermediate its ends on the adjacent block 17. A spring 91 acts on said latch to normally hold the same clear of the notch. The arm 83 has a member 92 depending therefrom, carrying an adjustable screw 93 positioned to engage and depress the head of the latch into the notch, only when the roller 84 is riding on the flat portion 86 of the disc 85.

The structure just described, from the part 75 to the part 93, constitutes the paper distinguisher, and press-operation control mechanism, as will be seen.

Besides the two ink plates, enabling two-color work to be turned out, I may also employ an ink ribbon to cover a portion of the type on the form between the radius of action of the ink-plate rolls. The winding and unwinding of this ribbon is controlled by a mechanism fully shown and described in my copending application on the same filed July 1st, 1924, Serial No. 723,514. This mechanism includes an arm 95 pivoted at one end on the frame 1 and operatively connected at its other end to the lower end of the arm 22.

The operation of the mechanism is as follows:

Assume to start that the bed 2 is at its forward limit of movement, and the arm 22 likewise, and that a sheet of paper 94 has already been fed onto and is now resting on the conveyor.

In this position of the parts, as shown in Figs. 1 and 2, the following conditions obtain:

The forward-end duct roll 33 has been drawn clear of the ink roll 28 and is engaged with the adjacent plate 4 on the bed 2, by reason of the engagement of the roller 37 with the sloping surface 39 of the plate 4. The forward end of the notch 49 of the bar 43 is then ahead of the corresponding pawl 50.

The rear-end duct roll, being clear of the adjacent plate 4, is engaged with the adjacent ink-roll 28.

The roller 73 of the arm 72 is resting on the low portion A of the cam 74, in which position of said arm, as previously described, the feed guides 69 are lowered to engage the tongues 70, and the drop rolls 62 are raised clear of the sheet 94. The latter can

thus only move along the conveyor to the rear ends of the guides 69, which then act as stops preventing further movement of the sheet.

When the sheet moves to this position, it must of course raise the shoe 76 to a level therewith, and in so doing, raises the ledge 78 to a level with the ledge 82 which is fixed with the arm 83. The roller on this arm is then engaged with the circular portion of the cam-disc 85, the screw 93 mounted on said arm is clear of the latch 90, and the latter by reason of the spring 91 connected thereto, is held clear of the notch 89 on the member 88. At this time, said notch is a certain distance ahead of the adjacent end of the latch.

With a rotative movement of the shaft 9 in a left hand direction (when looking at that side of the press shown on the drawings) the bed 2 moves to the rear, and the cylinder 19 turns in a right hand direction, and the upper end of the lever 24, by reason of the shape of the cam 26, moves toward the rear, imparting a similar movement to the arm 22. Movement of the latter of course gradually lowers the cylinder to the plane of the type form, on account of the arrangement of the eccentric shaft 18 relative to said arm.

The upper end of the arm 45 moves forwardly, and the bar 43 moves rearwardly, tending to cause the cam lug 43^a of said bar to be moved clear of the arm 45. Up to the extent of movement of the arm 22 which brings the high portion B of the cam 74 close to the roller 73, as shown in Figs. 7 and 9, no clearance of the members 43^a and 45 will be had, and so far the guides 69 are still lowered and the drop rolls raised, and the cylinder is only partially lowered.

At this time, however, with the rotation of the gear 15 and disc 85 attached thereto, the flat or low surface 86 of said disc is directly under the roller 84 of the arm 83.

Said roller 84, by reason of the spring 87 acting on the arm 83, tends to drop so as to rest on said low surface. A sheet of paper being on the conveyor however, as previously stated, said roller and arm can move down but very little, since the ledges 78 and 82 being in horizontal alinement, and in close relation, the latter abuts against the former, and the arm 83 is thus held from further movement.

The screw 93 on said arm will not then be lowered to depress the latch 90, and the latter therefore maintains its position clear of the notched disc 88, and the shaft 16 is free for further rotation.

With a slight further rotation of the shaft 9 therefore, the arm 22 is turned so that the high portion B of the cam 74 passes under roller 73, raising the arm 72, causing raising of the guides 69 and lowering of the drop

- rolls into engagement with the sheet, as shown in Fig. 6. The sheet is then free to pass to the feed rolls 71 and cylinder 19, and is fed to the former by the driving pressure of the lower tape roll 57 against the sheet. By the time the paper is engaged by the said feed rolls, the arm 22 has turned so that the roller 73 is resting on the portion C of the cam 74, as shown in Fig. 5. This 5 raises the drop rolls slightly, but does not lower the feed guides into interference with the sheet still passing thereunder. When the rear end of the sheet has passed beyond the shoe 76, the latter is free to drop to its 10 normal position between the tapes, and will do so as soon as the roller 84 again rides on the circular portion of the disc 85, which causes the formerly abutted ledges 78 and 82 to be released from each other.
- 15 In the meantime, with the continued rearward movement of the upper portion of the lever 24, the forward end of the arm 45 has moved ahead of and clear of the lug 43^a, and the arm 43 will drop at that end a distance 20 equal to the height of the portion 43^a, as will be seen from Fig. 5. The notch 49 in said bar is thus moved below the plane of the pawl 50, whose drop is limited by the stop pin 51. The bar is therefore free to 25 move beyond the pawl to permit the corresponding duct roll 33 to engage the ink roll 28 and receive a fresh supply of ink.
- 30 When the bed 2 reaches its rearmost limit of travel, the rear end duct roll is moved into engagement with the corresponding ink plate in the same manner as previously set forth at the outset of this description of operations.
- 35 The control bar 44 of said rear duct roll, being supported at its free end on the corresponding end of the bar 43, drops therewith when the arm 45 moves clear of the lug 43^a. The notch 49 and pawl 50 of said bar 44 are disposed relative to each other in a manner 40 similar to the arrangement of the corresponding members of the bar 43, and function similarly. In other words, before the arm 45 again engages the lug 43 and raises the bars with the reverse movement of the 45 parts had when the bed 2 is moving forwardly, the notch 49 of the bar 44 has passed ahead of the corresponding pawl 50, enabling the rear duct roll to again engage its ink roll.
- 50 The functioning of the parts as above described takes place only when a single sheet of a predetermined thickness is on the conveyor. Failure to feed a sheet onto the conveyor halts the normal functioning of certain parts without necessitating stopping of the press, in the following manner:
- 55 There being no sheet on the conveyor, the shoe 76 will not be raised, nor will the ledge 78, the latter remaining below the level of the ledge 82. Therefore when the disc 85 turns so that the flat portion 86 is below the roller 84 as shown in Figs. 7 and 10, (at which time the notch 89 in the member 88 is in line with the head of the latch 90) the roller 84 will drop to rest on said flat portion 86, since there is then no obstruction in the path of movement of the ledge 82 attached to the arm 83.
- 60 The arm 84 being thus dropped, the screw 93 thereon engages and depresses the latch 90 so that the latter moves into the notch 89, thus preventing further rotation of the shaft 16, in the same direction. This is clearly shown in Fig. 10.
- 65 The arm 22, which is fixed on said shaft, cannot then rotate further. One result is that the cam portion B will not pass under the roller 73, and the feed guides 69 and drop rolls 62 will not be raised and lowered respectively. A second result is that the cylinder while continuing to rotate, will not be lowered to the plane of the type form.
- 70 The third result is that by reason of the connecting rod 23 between the arm 22 and lever 24, the latter can no longer follow the cam for the time being, and will be held stationary. This prevents further movement of the arm 45 so that it will not clear the lug 43^a, and the bars 43 and 44 are held raised. This in turn causes the pawls 51 to 75 engage the notches in the bars 43 and 44 during the backward and forward movement respectively of said bars, preventing them from having their full travel, and thereby holding the duct rolls from engagement with the ink rolls. The duct rolls being thus kept from receiving a fresh supply of ink, even when they engage the ink plates with the movement of the respective plates thereover, no ink will of course be spread 80 onto the plates from the duct rolls, since the latter have none thereon.
- 85 The counter 52 will not be actuated, since the lever 24 being stationary, will not move the counter actuating arm 54.
- 90 Also, since the arm 22 is held stationary, the arm 95 will not be moved to shift the mechanism controlled thereby.
- 95 Of course upon the return movement of the bed 2 during the idle stroke of the press, the parts return to their starting positions, and if in the meantime a sheet has been fed onto the conveyor, the normal functioning 100 of the press will be resumed. Otherwise the above described cessation of vital operations 105 will continue to be effected.
- 110 If more than one sheet, or a sheet of under or over thickness than that for which the distinguisher mechanism is adjusted at the time, is fed onto the conveyor, the results as far as cessation of functioning of certain parts is concerned, remains the same 115 as above described in connection with the lack of a sheet on the conveyor.
- 120 Under any of the above stated conditions, 125

the shoe 76 will of course be raised, but in the case of a sheet of under thickness, the ledge 78 will not be raised to the level of the ledge 82, allowing the latter to move over the same when the flat disc portion 86 is under the roller 84 of arm 83. If the sheet is of excessive thickness, or more than one sheet in superimposed order, is on the conveyor, the ledge 78 will be raised above the level of the ledge 82, allowing the latter to move under the same when the arm 83 tends to drop. In either case, the ledge 78 fails to be located in a position such as will cause it to act as a stop to prevent movement of the ledge 82 and arm 83, and the latch 90 therefore is moved to a locking position with member 88.

By reason of the fact that the ledge 78 and shoe 76 are vertically adjustable relative to each other, as previously described, the said ledge may always be caused to horizontally align with the ledge 82 with a sheet of any thickness on the conveyor, and such alignment will of course be disturbed when a sheet of a different thickness is placed on the conveyor, as long as the ledge remains adjusted to suit sheets of that certain thickness for which the distinguisher is set.

If it is not desired that the duct rolls remain inactive under any of the conditions above set forth, the rod 46 is raised to withdraw the rearmost notch 47 therein from the holding pin 48, and is pulled back to allow the forward notch to engage the pin.

This moves the arm 45 clear of the lug 43^a at all times, and causes the bars 43 and 44 to be lowered so that the pawls 50 fail to engage the respective notches 49. This of course permits unrestricted movement of said bars and the duct rolls mounted in connection therewith.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. In a printing press having a type form, a printing cylinder arranged to be lowered into cooperative relation with the form, and a driven feed conveyor onto which the sheets to be printed are fed prior to passing to the cylinder, fingers disposed between the conveyor and the cylinder and normally projecting below the conveyor to form a stop for paper being fed to the cylinder, and means associated with the fingers for causing

the same to be raised clear of the conveyor only when a single sheet of a predetermined thickness is approaching the fingers.

2. A structure as in claim 1, in which the cylinder will only be lowered when said means is thus functioning.

3. In a printing press having a type form, a printing cylinder arranged to be lowered into cooperative relation with the form, and a feed conveyor onto which the sheets to be printed are fed prior to passing to the cylinder; stop means associated with the conveyor and normally disposed in the path of movement of a sheet toward the cylinder, and means preventing the lowering of the cylinder and the release of the stop means unless a single sheet of a predetermined thickness be on the conveyor.

4. In a printing press having a type form, a printing cylinder arranged to be lowered into cooperative relation with the form, and a feed conveyor onto which the sheets to be printed are fed prior to passing to the cylinder; stop means associated with the conveyor and normally disposed in the path of movement of a sheet toward the cylinder, and means actuated only by a single sheet of predetermined thickness on the conveyor for allowing the stop means to be released and the cylinder to be lowered.

5. A structure as in claim 1, in which means is provided between the cylinder and the finger actuating means for enabling the cylinder to be lowered only when the fingers are acted upon to be raised.

6. In a printing press having a type form, a printing cylinder arranged to be lowered into cooperative relation with the form, and a driven feed conveyor onto which the sheets to be printed are fed prior to passing to the cylinder, fingers disposed between the conveyor and the cylinder and normally projecting below the conveyor to form a stop for paper being fed to the cylinder, and means whose actuation is controlled only by a single sheet of paper of a predetermined thickness on the conveyor, for causing the fingers to be raised and the cylinder lowered, and whose actuation is controlled by more than a single sheet to prevent raising of the fingers and lowering of the cylinder.

7. In a printing press having a driven printing mechanism adapted to receive and print sheets, and a feed conveyor adapted to receive and feed sheets one by one to the printing mechanism; a sheet counting mechanism normally actuated with each printing movement of the printing mechanism, means preventing the actuation of the counting mechanism if a sheet is not fed to the printing mechanism, and means associated with the conveyor whereby such feeding will be prevented if more than one sheet of a predetermined thickness is on the conveyor.

8. In a printing press having a driven printing mechanism adapted to receive and print sheets, and a feed conveyor adapted to receive and feed sheets one by one to the printing mechanism; a sheet counting mechanism normally actuated with each printing movement of the printing mechanism, means preventing the actuation of the counting mechanism if a sheet is not fed to the printing mechanism, and means controlled by the presence of a single sheet of a predetermined thickness on the conveyor for then allowing such feeding to take place and the counting mechanism to be then actuated.
9. In a printing press having a driven printing mechanism adapted to receive and print sheets one by one, a sheet counting mechanism normally actuated with each printing movement of the printing mechanism, means whereby the counting mechanism will be actuated only if a sheet is fed to the printing mechanism, and means whereby such sheet will only be so fed if it is of a certain predetermined thickness.
10. In a printing press having a type-form and a printing cylinder adapted to be lowered into printing relation with the form, a counting mechanism adapted to register each sheet as it passes between the cylinder and form, a common means controlling the movement of the cylinder and counting mechanism, and means whereby such controlling means will not function unless a sheet is fed to the cylinder.
11. In a printing press having a moving bed carrying an ink plate and a type form, a printing cylinder arranged to cooperate with the form, an ink-fountain, and means for inking the ink plate from the fountain; a means whereby if a sheet is not fed to the cylinder the plate inking means will fail to function, and means whereby said inking means may be rendered operative at will regardless of the feeding of a sheet to the cylinder.
12. In a printing press having a reciprocating moving bed carrying ink plates at both ends and a type form therebetween, a printing cylinder arranged to cooperate with the form, and ink fountains for the respective plates; means for normally inking the plates from the respective fountains in alternating order with the reciprocation of the bed, and means whereby if a sheet is not fed to the cylinder, first one and then the other of the plate inking means will automatically fail to function.
13. In a printing press having a moving bed carrying an ink plate and a type form, a printing cylinder arranged to cooperate with the form, an ink-fountain, means for inking the ink plate from the fountain, means for feeding sheets to the cylinder one by one, and means associated with said feeding means whereby unless a single sheet of a predetermined thickness is fed thereon for passage to the cylinder, the plate inking means will fail to function.
14. In a printing press having a reciprocating moving bed carrying ink plates at both ends and a type form therebetween, a printing cylinder arranged to cooperate with the form, and ink fountains for the respective plates; means for normally inking the plates from the respective fountains in alternating order with the reciprocation of the bed, means for feeding sheets to the cylinder one by one, and means associated with said feeding means and controlled by the presence of a sheet thereon for controlling the functioning of the plate inking means in their proper order.
15. In a printing press having a moving bed carrying an ink plate and a type form, a printing cylinder arranged to cooperate with the form, an ink-fountain, means for inking the ink plate from the fountain, means for feeding sheets to the cylinder one by one, means whereby unless a sheet is fed to the cylinder the plate inking means will not function, and means controlled by the presence of a single sheet of a predetermined thickness on the feeding means for controlling the feeding of said sheet to the cylinder.
16. In a printing press having a reciprocating moving bed carrying ink plates at both ends and a type form therebetween, a printing cylinder arranged to cooperate with the form, and ink-fountain rolls for the respective plates; duct rolls adapted to be alternately engaged with the respective fountain rolls and plates with the reciprocation of the bed, means for feeding sheets to the cylinder one by one, means associated with the feeding means for controlling the passage of a sheet to the cylinder, means controlled by a single sheet of a predetermined thickness on the feeding means for actuating the control means, and means between said sheet controlled means and the duct rolls whereby the latter are alternately prevented from engagement with the ink plates unless said sheet-feeding control means is actuated.
17. In a printing press having a reciprocating moving bed carrying ink plates at both ends and a type form therebetween, a printing cylinder arranged to cooperate with the form, and ink-fountain rolls for the respective plates; duct rolls adapted to be alternately engaged with the respective fountain rolls and plates with the reciprocation of the bed, means for feeding sheets to the cylinder one by one, notched horizontal bars operatively connected at one end with the duct rolls and overlapping each other at their opposite ends, said bars being adapted for horizontal reciprocatory move-

ment with the reciprocation of the bed and the movement of the duct rolls; fixed pawls positioned to independently engage the notches in the bars intermediate the limits of travel of the latter, means whereby if a sheet is fed to the cylinder the bars will be moved clear of the pawls to enable the bars to move to their full extent, and means controlled by a sheet on the feeding means whereby if such sheet is not fed to the cylinder the bars will be held in position to be engaged by the pawls.

18. In a printing press having a reciprocating moving bed carrying ink plates at both ends and a type form therebetween, a printing cylinder arranged to cooperate with the form, and ink-fountain rolls for the respective plates; duct rolls adapted to be alternately engaged with the respective fountain rolls and plates with the reciprocation of the bed, means for feeding sheets to the cylinder one by one, notched horizontal bars operatively connected at one end with the duct rolls and overlapping each other at their opposite ends, said bars being adapted for horizontal reciprocatory movement with the reciprocation of the bed and the movement of the duct rolls; fixed pawls positioned to independently engage the notches in the bars intermediate the limits of travel of the latter; a cam-lug on the under side of the free end of the overlapped bar, an arm adapted to be normally engaged and disengaged with said lug to maintain the adjacent ends of the bars raised and lowered respectively, such lowering moving the bars clear of the pawls, and means controlled by a sheet on the feeding means for controlling the movement of the arm.

40 19. In a printing press having a reciprocating moving bed carrying ink plates at both ends and a type form therebetween, a printing cylinder arranged to cooperate with the form, and ink-fountain rolls for the respective plates; duct rolls adapted to be alternately engaged with the respective fountain rolls and plates with the reciprocation of the bed, means for feeding sheets to the cylinder one by one, notched horizontal bars operatively connected at one end with the duct rolls and overlapping each other at their opposite ends, said bars being adapted for horizontal reciprocatory movement with the reciprocation of the bed and the movement of the duct rolls; fixed pawls positioned to independently engage the notches in the bars intermediate the limits of travel of the latter, a cam-lug on the under side of the free end of the overlapped bar, an arm normally reciprocating with the reciprocation of the bed and adapted to normally engage and move clear of the lug whereby to respectively raise and lower the free ends of the bars, such lowering moving the bars clear of the pawls, means con-

nected to the arm for thus actuating the same, means controlled by the passage of a sheet to the cylinders for controlling the movement of the arm actuating means, and means controlled by such sheet itself whereby unless the latter is of a predetermined thickness it will not be fed to the cylinder and the arm actuating means will be held stationary with the arm in the bar raising position.

75 20. In a printing press, a reciprocating type form, a rotary printing cylinder arranged to cooperate therewith, an eccentric shaft on which the cylinder is mounted, means attached to the shaft for causing the same to be turned to lower the cylinder into printing relation with the form at predetermined periods, a feed conveyor to receive sheets to be fed to the cylinder, a notched lug on the shaft, a latch adapted to engage said notch before the cylinder is lowered to its full extent but normally held clear of the plane of the notch, means for moving the latch to engage the notch, and means associated with the conveyor and actuated by a single sheet of a predetermined thickness thereon for holding the latch moving means inactive.

80 21. In a printing press, a type form and a printing cylinder adapted to be lowered into cooperative relation therewith at predetermined times; means for feeding sheets to the cylinder one by one, a commonly actuated means for reciprocating the form, rotating the cylinder and lowering the latter independent of its rotation, and means whereby unless a sheet is fed to the cylinder the latter will not be lowered but the reciprocation of the form and rotation of the cylinder will not be interfered with.

85 22. In a printing press, a type form and a printing cylinder adapted to be lowered into cooperative relation therewith at predetermined times; an eccentric shaft on which the cylinder is mounted, means for feeding sheets to the cylinder one by one, a shoe on the sheet feeding means raised by a sheet thereon, a commonly actuated means for reciprocating the form, rotating the cylinder and turning the shaft to cause the cylinder to be lowered independent of its rotation, and means whereby unless said shoe is raised to a predetermined level the shaft will be held from turning but the reciprocation of the form and rotation of the cylinder will not be interfered with.

90 23. In a printing press, a reciprocating type form, a rotary printing cylinder arranged to cooperate therewith, an eccentric shaft on which the cylinder is mounted, means attached to the shaft for causing the same to be turned to lower the cylinder into printing relation with the form at predetermined periods, a feed conveyor to receive sheets to be fed to the cylinder, latch means

- for holding the shaft from turning but normally disengaged therefrom, a shoe on the sheet feeding means raised by a sheet thereon, and means between said latch means and shoe whereby unless the latter is raised to a predetermined level the latch will be moved to a latching position with the shaft.
24. In a printing press, a reciprocating type form, a rotary printing cylinder arranged to cooperate therewith, an eccentric shaft on which the cylinder is turnably mounted, means connected to the shaft for causing the same to be turned to lower the cylinder into printing relation with the form at predetermined periods, a feed conveyor to receive sheets to be fed to the cylinder, latch means for holding the shaft from turning but normally disengaged therefrom, a shoe on the conveyor raised by a sheet thereon, a ledge mounted with the shoe and projecting at an angle thereto, a pivotally mounted ledge adapted to align with the shoe ledge when the latter is raised by a sheet of predetermined thickness on the conveyor, and means whereby unless such alignment is had at a predetermined period in the rotation of the cylinder the latch will be moved to engage and hold the shaft from turning.
25. In a printing press, a reciprocating type form, a rotary printing cylinder arranged to cooperate therewith, an eccentric shaft on which the cylinder is turnably mounted, means connected to the shaft for causing the same to be turned to lower the cylinder into printing relation with the form at predetermined periods, a feed conveyor to receive sheets to be fed to the cylinder, latch means for holding the shaft from turning but normally disengaged therefrom, a shoe on the conveyor raised by a sheet thereon, a ledge mounted with the shoe and projecting at an angle thereto, a pivotally mounted arm having a ledge mounted therewith at its pivoted end and facing the shoe-ledge, said ledges being in horizontal alignment when a sheet of a predetermined thickness raises the shoe, means associated with the arm whereby at a predetermined period of the rotation of the cylinder the ledges will abut and prevent lowering movement of the free end of the arm, and means whereby the shaft latch means will be then maintained inactive.
26. In a printing press, a reciprocating type form, a rotary printing cylinder arranged to cooperate therewith, an eccentric shaft on which the cylinder is turnably mounted, means connected to the shaft for causing the same to be turned to lower the cylinder into printing relation with the form at predetermined periods, a feed conveyor to receive sheets to be fed to the cylinder, latch means for holding the shaft from turning but normally disengaged therefrom, a shoe on the conveyor raised by a sheet thereon, a ledge mounted with the shoe and projecting at an angle thereto, a pivotally mounted arm having a ledge mounted therewith at its pivoted end and facing the shoe-ledge, said ledges being in horizontal alignment when a sheet of a predetermined thickness raises the shoe, latch actuating means mounted with the arm, a roller on the free end of the arm, and a cam disc rotating with the cylinder and on which the roller normally rides, said disc having a flat surface disposed so that if the roller rests thereon the latch will be actuated; the ledges, if aligned, abutting and preventing dropping of the arm when with the rotation of the disc the flat portion thereof moves under the roller.
27. In a printing press, a reciprocating type form, a rotary printing cylinder arranged to cooperate therewith, an eccentric shaft on which the cylinder is turnably mounted, means connected to the shaft for causing the same to be turned to lower the cylinder into printing relation with the form at predetermined periods, a feed conveyor to receive sheets to be fed to the cylinder, latch means for holding the shaft from turning but normally disengaged therefrom, a shoe on the conveyor raised by a sheet thereon, a ledge mounted with the shoe and projecting at an angle thereto, a pivotally mounted arm having a ledge mounted therewith at its pivoted end and facing the shoe-ledge, said ledges being in horizontal alignment when a sheet of a predetermined thickness raises the shoe, latch actuating means mounted with the arm, a roller on the free end of the arm, and a cam disc rotating with the cylinder and on which the roller normally rides, said disc having a flat surface disposed so that if the roller rests thereon the latch will be actuated; the ledges, if aligned, abutting and preventing dropping of the arm when with the rotation of the disc the flat portion thereof moves under the roller.
28. In a printing press, a reciprocating type form, a rotary printing cylinder arranged to cooperate therewith, an eccentric shaft on which the cylinder is turnably mounted, means connected to the shaft for causing the same to be turned to lower the cylinder into printing relation with the form at predetermined periods, a feed conveyor to receive sheets to be fed to the cylinder, latch means for holding the shaft from turning but normally disengaged therefrom, a shoe on the conveyor raised by a sheet thereon, an arm pivoted at one end, a roller on the other end of the arm, latch actuating means mounted with the arm and normally clear of the latch, a cam disc rotating with the cylinder and on which the roller normally rides, said disc having a flat surface disposed so that if the roller rests thereon the latch will be actuated, and means between the arm and shoe preventing dropping of the roller onto said flat surface only when

a sheet of a predetermined thickness is under the shoe.

29. In a printing press, a reciprocating type form, a rotary printing cylinder arranged to cooperate therewith, an eccentric shaft on which the cylinder is turnably mounted, means connected to the shaft for causing the same to be turned to lower the cylinder into printing relation with the form at predetermined periods, a feed conveyor to receive sheets to be fed to the cylinder, latch means for holding the shaft from turning but normally disengaged therefrom, a shoe on the conveyor raised by a sheet thereon, a ledge mounted with the shoe and projecting at an angle thereto, a pivoted arm having a ledge mounted therewith at its pivoted end and facing the shoe-ledge, said ledges being in horizontal alinement when a sheet of a predetermined thickness raises the shoe, latch actuating means mounted with the arm, means whereby unless said ledges are in horizontal alinement at a predetermined period in the rotation of the cylinder the latch will be actuated to hold the shaft from rotation, and means for adjusting the angular setting between the shoe and its ledge, whereby the latter may be caused to aline with the arm ledge with sheets of different thicknesses under the shoe.
30. In a printing press, a reciprocating type form, a rotary printing cylinder arranged to cooperate therewith, an eccentric shaft on which the cylinder is turnably mounted, means connected to the shaft for causing the same to be turned to lower the cylinder into printing relation with the form at predetermined periods, a feed conveyor to receive sheets to be fed to the cylinder, latch means for holding the shaft from turning but normally disengaged therefrom, a shoe on the conveyor raised by a sheet thereon, a ledge mounted with the shoe and projecting at an angle thereto, the horizontal level of the ledge when the shoe is raised depending on the thickness of the sheet under the shoe, a pivotally mounted ledge adapted to aline with the shoe ledge when the latter is raised to the height determined by the thickness of the sheet under the shoe, adjusting means between the ledges enabling the common level to be had with different thicknesses of sheets, and means operatively connected with the pivotally mounted ledge whereby unless such alinement is had at a predetermined period in the rotation of the cylinder, the latch will be moved to engage and hold the shaft from turning.
31. In a printing press, a reciprocating type form, a rotary printing cylinder arranged to cooperate therewith, an eccentric shaft on which the cylinder is turnably mounted, means connected to the shaft for

causing the same to be turned to lower the cylinder into printing relation with the form at predetermined periods, a feed conveyor to receive sheets to be fed to the cylinder, latch means for holding the shaft from turning but normally disengaged therefrom, a shoe on the conveyor raised by a sheet thereon, stop means on the conveyor normally preventing passage of a sheet to the cylinder, a shoe on the conveyor raised by a sheet thereon, means between the shoe and shaft whereby unless a sheet under the shoe is of a predetermined thickness the shaft will be prevented from turning, and means controlled by the turning of the shaft for releasing the stop means.

32. In a printing press, a reciprocating type form, a rotary printing cylinder arranged to cooperate therewith, an eccentric shaft on which the cylinder is turnably mounted, means connected to the shaft for causing the same to be turned to lower the cylinder into printing relation with the form at predetermined periods, a feed conveyor to receive sheets to be fed to the cylinder, latch means for holding the shaft from turning but normally disengaged therefrom, a shoe on the conveyor raised by a sheet thereon, stop means on the conveyor normally preventing passage of a sheet to the cylinder, a shoe on the conveyor raised by a sheet thereon, means between the shoe and shaft whereby unless a sheet under the shoe is of a predetermined thickness the shaft will be prevented from turning, and means controlled by the turning of the shaft for releasing the stop means.

33. In a printing press, a reciprocating type form, a rotary printing cylinder arranged to be lowered into printing relation with the form at a predetermined period in the reciprocation of the latter, an ink plate mounted with the type form, a counting mechanism for the sheets as they are printed, a common lever controlling the lowering of the cylinder, actuation of the counting mechanism and actuation of the plate inking means, and means holding said lever inactive unless a sheet of paper is fed to the cylinder.

34. In a printing press, a reciprocating type form, a rotary printing cylinder arranged to be lowered into printing relation with the form at a predetermined period in the reciprocation of the latter, an ink plate mounted with the type form, a counting mechanism for the sheets as they are printed, a common lever controlling the lowering of the cylinder, actuation of the counting mechanism and actuation of the plate inking means, a sheet feeding means to receive

sheets to be printed, and means whereby unless a sheet of a predetermined thickness is on the feeding means said lever will be held inactive and the sheet will not be fed to the cylinder.

35. In a printing press, a reciprocating type form, a rotary printing cylinder arranged to be lowered into printing relation with the form at a predetermined period in the reciprocation of the latter, an ink plate mounted with the type form, a counting mechanism for the sheets as they are printed, a common lever controlling the lowering of the cylinder, actuation of the counting mechanism and actuation of the plate inking means, a sheet feeding means to receive sheets to be printed, and means controlled by the presence of a sheet of predetermined thickness on the conveyor for controlling the operation of the lever.

36. In a printing press, a reciprocating type form, a rotary printing cylinder arranged to be lowered into printing relation with the form at a predetermined period in the reciprocation of the latter, an ink plate mounted with the type form, a counting mechanism for the sheets as they are printed, and means whereby unless a sheet is fed to the conveyor the cylinder will not be lowered, the counting mechanism will not be actuated, and the plate will not be inked.

37. In a printing press, a reciprocating type form, a rotary printing cylinder arranged to be lowered into printing relation with the form at a predetermined period in the reciprocation of the latter, an ink plate mounted with the type form, a counting mechanism for the sheets as they are printed, a common lever controlling the lowering of the cylinder, actuation of the counting mechanism and actuation of the plate inking means, a sheet feeding means to receive sheets to be printed, means controlled by the presence of a sheet of predetermined thickness on the conveyor for controlling the operation of the lever, and means whereby unless said sheet be of a predeter-

mined thickness the lever will be held inactive.

38. In a printing press, a reciprocating type form, a rotary printing cylinder arranged to be lowered into printing relation with the form at a predetermined period in the reciprocation of the latter, an ink plate mounted with the type form, a counting mechanism for the sheets as they are printed, a common lever controlling the lowering of the cylinder, actuation of the counting mechanism and actuation of the plate inking means, a sheet feeding means to receive sheets to be printed, stop means on the feeding means normally preventing passage of a sheet to the cylinder, means between the lever and stop means whereby the latter is only released upon the movement of the former, and means associated with the feeding means whereby unless a sheet of a predetermined thickness be on the feeding means, the lever will be held inactive.

39. In a printing press, a reciprocating type form, a rotary printing cylinder arranged to be lowered into printing relation with the form at a predetermined period in the reciprocation of the latter, an ink plate mounted with the type form, a counting mechanism for the sheets as they are printed, a common lever controlling the lowering of the cylinder, actuation of the counting mechanism and actuation of the plate inking means, a sheet feeding means to receive sheets to be printed, stop means on the feeding means normally preventing passage of a sheet to the cylinder, means controlled by the presence of a sheet on the feeding means for enabling the stop means to be released and the lever actuated, and means whereby such stop means will not be released, and the lever will be held inactive if no sheet, more than one sheet, or a sheet of greater than a predetermined thickness, be on the feeding means.

In testimony whereof I affix my signature.

CHARLES L. LOW.
